Filed Feb. 22, 1971, Ser. No. 117,849

Term of patent 14 years

Int. Cl. D24—02

U.S. Cl. D16—2

FIG. 2

FIG. 3

FIG. 1

FIG. 1 is a perspective view of a device for electrochemical analysis showing my design and particularly the rear, top and one side thereof;

FIG. 2 is a side view of the device shown in FIG. 1; and

FIG. 3 is a rear view of the device shown in FIG. 1.

The undisclosed front portion of the device is plane and follows the general outline of said front portion as best illustrated in FIGS. 1 and 2 on the drawing.

I claim:

The ornamental design for a device for electrochemical analysis, substantially as shown and described.
